UNITED STATES PATENT OFFICE.

HEINRICH KOPPERS, OF CARNAP, NEAR ESSEN, GERMANY.

REGENERATIVE COKE-OVEN.

SPECIFICATION forming part of Letters Patent No. 738,918, dated September 15, 1903.

Application filed December 28, 1901. Serial No. 87,641. (No model.)

To all whom it may concern:

Be it known that I, HEINRICH KOPPERS, coking engineer, a subject of the German Emperor, residing at Carnap, near Essen, in the German Empire, have invented new and useful Improvements in Regenerative Coke-Ovens with Separate Distribution of Gas and Air to the Heating-Flues, of which the following is a specification.

10 This invention relates to regenerative coke-ovens, the construction of which is improved in such a manner that a separate distribution of gas and air to the heating-flues is obtained and that the nozzles for the supply of the air 15 are situated in such a manner that they do not come in contact with the flames.

In the accompanying drawings the improved regenerative coke-oven is shown in Figure 1 in a vertical section, the left half of 20 the drawing being a section on line A B of Fig. 2, showing a coking-chamber, and the right half being a section on line C D of Fig. 2, showing the arrangement of the heating-flues. Fig. 2 is a cross-section on line E F of 25 Fig. 1. Fig. 3 shows in vertical section, on a larger scale, the bottom of a heating-flue with the nozzles; and Fig. 4 shows in vertical section, on a larger scale, the cover-plate of a heating-flue.

30 In the regenerative coke-oven the coking-chambers 1 and the heating-flues 2 are arranged, as usual, above the air-regenerators 3 and the gas-regenerators 4, respectively. Below the bottom of the coking-chambers 1 35 the air-distributing channels 5 are arranged, which communicate, by means of vertical channels 6, with the air-regenerators 3. Below the heating-flues 2 the gas-distributing channels 7 are situated, which are connected with 40 the gas-regenerators 4 by means of vertical channels 8. The gas-distributing channels 7 communicate with the heating-flues 2 by means of vertical borings in the center of the bottom of the heating-flues, into which openings removable nozzles 9 are inserted, which 45 may suitably have a conical form. The upper end of these nozzles 9 project slightly from the upper surface of the bottom of the heating-flue.

50 The air-distributing channels 5 communicate with the heating-flues 2 by means of horizontal nozzles 10, which are inserted into hori-

zontal borings of the side walls 11 of the heating-flues 2. In these side walls 11 recesses 12 are arranged at the place where the nozzles 10 of the air-distributing channels are situated, so that these nozzles 10 stand back from the heating-flues 2.

Above the heating-flues 2 the horizontal flue 13 for the gases of combustion is situated, as usual, which communicates with the several heating-flues 2 by vertical openings 14. Vertically above each heating-flue 2 an opening 15 is provided in the top wall 16 of the oven, which opening is closed by a removable cover-plate 17.

The coking-chambers 1 have the usual charge-ports 18 for the coals.

The nozzles 9 on the bottom of the heating-flues 2 can be inspected from outside the oven 70 after the cover-plates 17, closing the openings 15 in the top wall 16, have been removed, as the nozzles 9 stand perpendicularly below said openings 15. Thus it is possible to remove these nozzles 9 by means of long iron 75 tongs or rods from outside the oven and replace the same by fresh nozzles, if required.

The separate distribution of gas and air to the heating-flues is obtained as follows: The heating-gases mount from the gas-regenerators 4 through the vertical channels 8 to the gas-distributing channels 7 below the heating-flues and flow from here through the nozzles 9 into the heating-flues 2. The air for combustion is supplied from the air-regenerators 3 through the vertical channels 6 to the air-distributing channels 5 and through the horizontal nozzles 10 to the several heating-flues 2. The ignition of the heating-gases takes place above the nozzles 9 10 as soon 90 as the flow of air of combustion unites with the flow of heating-gases. The gases of combustion flow through the openings 14 into the horizontal flue 13 and are thence guided to the air and gas regenerators 4 or to the chimney, as required.

Having fully described my invention, what I claim by Letters Patent is—

Improvement in regenerative coke-ovens comprising in combination with the usual 100 coking-chambers and the heating-flues, gas-regenerators and air-regenerators below said coking-chambers and heating-flues, gas-distributing channels below the bottom of the

heating-flues, air-distributing channels below the ovens and with which the air-regenerators communicate, covering-arches above the heating-flues, vertical borings in the bottom 5 of the heating-flues placed perpendicularly below the openings in the covering-arches of the heating-flues, said vertical borings communicating with the gas-distributing channels, removable nozzles in said borings, recesses in the side walls of the heating-flues close to the bottom of the same, horizontal borings in the side walls of the air-channels connecting the same with the recesses in the side walls of the heating-flues, nozzles in said

horizontal borings, openings in the top wall 15 of the oven above the gas-channels at the upper end of the heating-flues and removable cover-plates closing said openings in the top wall of the oven, substantially as described and shown and for the purpose set forth. 20

In testimony whereof I have hereunto set my hand in presence of two subscribing witnesses.

HEINRICH KOPPERS.
